UNITED STATES PATENT OFFICE.

GUY M. RUSSELL, OF ROCHESTER, NEW YORK, ASSIGNOR TO AMERICAN PIANO COMPANY, OF NEW YORK, N. Y., A CORPORATION OF NEW JERSEY.

AUTOMATIC MUSICAL INSTRUMENT.

1,409,487.

Specification of Letters Patent. Patented Mar. 14, 1922.

Application filed September 15, 1915, Serial No. 50,876. Renewed December 28, 1921. Serial No. 525,349.

To all whom it may concern:

Be it known that I, GUY M. RUSSELL, a citizen of the United States, and a resident of Rochester, county of Monroe, and State 5 of New York, have invented an Improvement in Automatic Musical Instruments, of which the following description, in connection with the accompanying drawings, is a specification, like characters on the drawings 10 representing like parts.

This invention relates to automatic or partly automatic player pianos and pertains more particularly to the organization of controlling apparatus or elements in structural units such that they may be assembled 15 and adjusted apart from the instrument itself and then applied as a unit to the instrument.

One of the objects of the invention is to 20 supply a structural unit comprising various controlling elements which may be adjusted respectively and in relation to each other in the desired final adjustments before being placed in the musical instrument, such as a 25 player piano or the like; and when installed in the instrument, nothing requires to be done but to connect the unit with other working parts by simple tubes or links which serve to complete the organized automatic or partly automatic instrument. 30

The character of the invention may be 35 readily understood by reference to one practicable embodiment which has proved successful in use and is shown for illustration in the accompanying drawings, in which:

Fig. 1 is a plan view of the unit detached from a player piano;

Fig. 2 is a front elevation of the unit shown in Fig. 1;

Fig. 3 is a detailed section on the line 3-3 of Fig. 2;

Fig. 4 is a side elevation of the unit shown in Fig. 1;

Fig. 5 is a detailed section on the line 45 5-5 of Fig. 2;

Fig. 6 is a cross section on the lines 6-6 of Figs. 1 and 4;

Fig. 7 is a detailed side elevation partly in section on the line 7-7 of Fig. 6.

50 The specific controlling unit illustrated in the drawings comprises apparatus for controlling and operating a pedal mechanism as, for example, the so-called soft pedal, or the damper pedal; apparatus for governing the

speed of travel of the music sheet to main- 55 tain it uniform; apparatus for varying the speed of travel of the music sheet; manually operable means for varying the intensity of playing; regulating means for maintaining uniformity of playing intensities whether 60 one or many notes be sounded at a time; automatic means for varying playing intensities; automatic means for producing crescendo and diminuendo effects in connection 65 with the regulation; and means for causing the note sheet motor, upon re-winding, to be operated by the maximum degree of exhaust from the feeder bellows without utilizing the operation of the speed governor. All 70 of these different sets of apparatus are as- 75 sembled and secured in cooperative relation in a single structural unit such that all may be mounted in the unit and adjusted re- 80 spectively and in relation to each other and then the whole may be inserted as a unit 85 in the instrument and coupled by simple means with other operating parts thereof.

The various parts of the unit, in the illus- 90 trative instance, are mounted upon a base board 10 which by being appropriately 95 channelled as presently described provides conduits leading to various different parts. For instance a collared tube 11 provides means for attaching a pipe leading to the feeder bellows of any practicable type which, for the present purposes, will be assumed to be suction bellows. A conduit 12 leads to the music sheet motor. It is assumed that the music sheet motor is a pneumatic motor of usual type. A tube 13 provides means for connection with the action chest of the striker pneumatics. Thus when the unit is inserted in the playing instrument only a single connection need be made with the feeder bellows, i. e. at the collared tube 11; 95 another connection with the action chest by the tube 13 and a third connection with the note sheet motor by the pipe 12. Obviously these connections may be very readily made by flexible pipes and may be equally 100 readily broken if, for any purpose, it is desired to remove the unit.

The pedal operating mechanism will be first described. To simplify the usual pedal mechanism for either a damper or soft pedal, 105 a pedal rod 15 is shown in Figs. 6 and 7 having a pin 16 normally resting in a leather or other flexible stirrup 17 supported upon a

bracket 18 secured near the heel of the movable board of a pedal operating bellows 19. As shown in section in Fig. 7 and in dotted lines in Fig. 6, the bellows 19 has an open 5 port 20 extending clear through the base board 10 of the unit, and a channel 21 leading from said port 20 to a valve chamber 22. An adjustably acting valve 23 in said chamber admits, alternatively, atmosphere and 10 exhaust to the channel 21 and the pneumatic 19. The exhaust chamber 25 beneath the valve 23 (Fig. 6) is entered by a passage 26 connected by a duct 27 with another duct 28 connected with the tube 11 which leads to 15 the feeder bellows. Both of the ducts 27 and 28 are provided by channels formed in the rear of the base board 10. Thus the maximum exhaust is present in the exhaust chamber 25 and the appropriate action of 20 the valve 23 opens the pedal pneumatic 19 from time to time to the high exhaust. To muffle the sound of operation of the valve 23 a felt muffler 30 may be provided, of any practicable form. The valve 23 is a secondary 25 valve operated by the diaphragm over a chamber 32 which chamber is controlled by a double-acting valve 33 operated in turn by the diaphragm of a chamber 34, the latter chamber being connected (Fig. 1) by a duct 30 35 with the pedal operating vent in the tracker bar.

When a music sheet is being re-wound after playing, the pedal perforations in the sheet move over the pedal vent in the tracker bar in reverse order and have a tendency to repeat the operation of the pedal pneumatic 19 by opening and closing the vent. To prevent the chattering of the pedal operating apparatus during this re-winding, the primary valve 33 is held down during all 35 the re-winding, with sufficient force to hold the valve 33 closed in spite of the opening of the pedal operating vent and consequent admission of atmosphere to the diaphragm chamber 34. This is accomplished by a finger 40 overlying the top of the valve 33, and carried upon the movable board of a pedal-stop pneumatic 41 which is connected by a duct 42 with a chest 43 for regulated air 45 presently referred to. During all the normal or playing operation of the instrument, regulated air is present in the chest 43, and through the duct 42, produces a condition of 50 exhaust in the pneumatic 41 thereby somewhat collapsing the latter and holding the finger 40 away from operative contact or relation with the valve 33 and lifting the valve free to operate in a normal way so as to control the pedal action. Upon the re-winding, however, the supply of regulated air is cut off from the chest 43 and atmosphere admitted thereto and therethrough to the pneumatic 41, permitting the spring 45 to expand said pneumatic 41 and move the 55 finger down into position to hold the valve 60

33 in closed position as described, so that the 65 pedal mechanism is prevented from operating during the re-winding.

The pedal bellows 19 carries an adjustable 70 stop 47 to prevent too great collapse of the pneumatic and is provided with a stop 48 to prevent too great expansion of the pneumatic.

Referring again to the flexible stirrup 17 suspended from the heel of the pedal pneumatic 19, the flexibility thereof permits the 75 pedal rod 15 to be operated in the usual manner by the foot pedal without interference from the automatic apparatus while, at the same time, provides effectively for a 80 positive actuation of the rod by the pneumatic 19.

The governor for the note sheet motor will be next described. The illustrative construction is shown in Figs. 3 and 6. In Fig. 85 6 the cover 50 for the movable board of the pneumatic is removed to disclose the interior. The governor pneumatic 51 has a port 52 controlled by a throttle valve 53 mounted upon a pivot 54 and having its rear end engaged by a pin 55 which contacts with the inner face of the movable board 50. The port 52 leads into a chamber 56 which is a part of the high exhaust chamber 28 shown in dotted lines in Fig. 6. The governor 90 pneumatic 51 has also a port 58 which as shown in Fig. 6, in dotted lines, is connected by a channel 59 with a port 60 leading into the valve box of the tempo controlling valve. As will be well understood in the art, the 100 pneumatic 51 with its throttle valve 53, is simply a regulator pneumatic which maintains uniform the degree of tension at the port 58 in the channel 59 and at the port 60; in other words, the flow of air through these 105 ports is maintained at a uniform speed by the governor pneumatic 51, except so far as the tempo controlling valve presently referred to may modify the flow of air to change the speed of travel of the music 110 sheet.

Turning next to the tempo controlling valve, the same is shown in front elevation in Fig. 6 and in side elevation in Fig. 5, the tempo controlling valve itself being indicated by the numeral 62.

The valve 62 has a stem 63 which extends upwardly through the valve box 64 and is connected by a link 65 with the horizontal arm 66 of a bell crank lever. This lever is mounted upon a bracket 67 and the vertical arm 68 thereof is arranged to be connected with any desired manual or other controlling means by which the tempo valve may be operated. The valve box 64 has a port 70 120 leading to a channel 71 (see dotted lines Fig. 6), said channel being formed in the base board 10 and extending up to the pipe 12 by which connection is made with the note sheet motor. Evidently the closure of 130

the port 60 to a greater or less extent by the valve 62 will vary the flow of air from the note sheet motor and will consequently vary the speed of that motor and the speed of travel of the note sheet; while at the same time the operation of the governor pneumatic 51 will maintain uniform the speed of the motor for any given adjustment of the tempo valve 62.

- 10 When the note sheet is being re-wound after playing, it is desired to travel at maximum speed and in such circumstances the inter-position of the governor pneumatic 50 and the tempo valve 62 is superfluous. Accordingly, a suitable by-pass arrangement is made by which the maximum exhaust direct from the feeder bellows may be introduced to the note sheet motor for re-winding, or, if desired, for driving it at maximum speed in either direction. For this purpose the valve box 64 has another port 72 (see dotted lines Fig. 6) connected by a channel 73 formed in the base board 10, with the high exhaust channel 28 already referred to. Normally the port 72 is closed by a slide valve 75 having a stem 76 suitably mounted to open and close the valve 75. The stem 76 is connected by a link 77 with the bell crank lever 78 arranged to be connected with any suitable manually or other controlled means. Whenever desired, the valve 75 may be moved downwardly to open the port 72 thereby opening the interior of the valve box 64 to high exhaust which will draw air at maximum speed through the port 70, duct 71 and pipe 12 to drive the note sheet motor at high speed. It is preferred to couple the bell crank lever 78 or its equivalent or substitute, with reversing mechanism which causes the note sheet to be re-wound, the purpose being to open the valve port 72 automatically upon the starting of the re-winding operation; but since it will be understood that the parts referred to as elements of the action unit may be connected in any desired manner with other parts of the instrument, it is unnecessary for present purposes to illustrate the arrangement just described.
- 50 Turning now to the several expression controlling mechanisms, the apparatus shown in the present drawings by the three regulator pouches 80, 81 and 82 mounted upon a stationary board 83 and connected to a common movable board 84 hinged at 85 to a part which is bracketed to the base board 10. At its free end the common movable board 84 of said regulator pouches, carries a valve stem 86 of a throttle valve 86' which stands between a high exhaust chest 87 and a regulated exhaust chest 88. On the upper side of the movable board 84 is a pouch 90 which is kept always partially exhausted so that it serves somewhat the purpose of a spring pulling upwardly on the

movable board 84 and opposing the downward pull of the pouches 80, 81 and 82 when they are partially exhausted. By suitable means well known in the art, atmosphere or regulated tension may be admitted alternatively to any one or more of the pouches 80, 81 and 82 and by the selective admission of either atmosphere or regulated tension to these pouches the regulating action may be modified to produce distinct increments of change in the degree of exhaust in the regulated tension chest 88 and thereby distinct increments of change in the playing intensities. The valve actions by which the admission of atmosphere or regulated tension to the pouches 80, 81 and 82 is controlled, are enclosed in the primary valve box 92 and the secondary action box 93. From the primary action box 92 ducts 93', 94, 95 and 96 lead to appropriate tracker vents by which the admission of atmosphere and regulated tension to the several pouches 80, 81 and 84 is controlled.

Provision is made for maintaining a uniform degree of exhaust in the upper pouch 90 in order to produce a desirable refinement of regulation; and this is effected by means of a second regulating pneumatic 98 which operates a needle valve 99 in a manner unnecessary to be described herein after but with the result of maintaining normally a uniform degree of exhaust in the pouch 90.

Cooperating with the needle valve 99 is a further valve 100 which prevents excess operation of the needle valve.

Crescendo and diminuendo effects are produced in the same manner that excess operation of the needle valve is prevented, through the tracker which is connected by ducts 101, 102, with appropriate parts of the valve action for the valve 100.

Returning now to Fig. 6, the regulated tension chest 43 communicates with the regulated tension chest 88 shown in Fig. 2, that is to say, the throttle valve controlled by the regulator pouches 80, 81 and 82 regulates and also varies the degree of exhaust in the chest 43 and therefore the degree of exhaust which is communicated to the striker pneumatics through the pipe 13 which leads to the action chest for the striker pneumatics.

It has already been explained that when regulated tension is admitted to various combinations or permutations of the pouches 80, 81 and 82, distinct increments of change in the regulation and in playing intensities are produced. These effects may be modified by permitting atmosphere to leak more or less into that supply of regulated exhaust which is opened into the pouches 80, 81 and 82, and to provide for such a leakage of atmosphere a double-acting valve 110 is provided as shown in Fig. 6. Connected

with the regulated exhaust chest 43 is a duct 111 which leads indirectly to the chest for the pouches 80, 81 and 82, i. e. indirectly past the valve 110. This valve comprises 5 a cone-shaped throttle valve 112 and a disk valve 114. The former acts as a needle valve to throttle the flow of regulated tension into the duct 111 from a chamber 116. A chamber 118 has an atmosphere bleed 119 and 10 when the valve 110 is lifted slightly the flow of regulated tension past the cone valve 112 is somewhat restricted and at the same time some atmosphere is permitted to leak from the chamber 118 into the chamber 116 thereby diminishing the degree 15 of exhaust which is communicated from the chamber 116 to those of the pouches 80, 81 and 82 which are selected for the admission of regulated exhaust. A duct (not 20 shown) leads from the chamber 116 shown in Fig. 6 to the secondary valve chest 93 (Fig. 2) from which the pouches 80, 81 and 82, as selected, receive the regulated exhaust.

The stem of the valve 110 is connected to 25 a bell crank lever 120 which in assembling with the instrument may be connected to any manual or other contrivance for controlling the valve 110.

As shown in Fig. 6, the channel 28 leading 30 from the source of high exhaust opens into a duct 122 which leads directly into the high exhaust chest 87 shown in Fig. 2.

A so-called equalizer 125 is connected by 35 a duct 126 with the upper pouch 90.

Reference has already been made to the provision of means for preventing the playing of the striking pneumatics during the re-winding of the note sheet. This is effected by means of a cut-off pneumatic 130 (Fig. 2), having on its movable board 131 a lever 132 which overlies the collar 133 upon the stem 86 of the main throttle valve. Obviously when the pneumatic 130 is collapsed it pulls down the throttle valve and 45 cuts off communication between high exhaust and regulated exhaust so that the supply of regulated exhaust to the player pneumatic action chest is closed. The size of the pneumatic 130 is made sufficient for 50 this purpose. The valve box 135 for the pneumatic 130 is connected by a pipe 136 with the source of high exhaust and by a tube 138 with a valve of any practicable sort, as, for instance, a tracker vent or, preferably, a valve controlled by the reverse mechanism which operates to start the re-wind of the note sheet. The valve box 135 contains merely a conventional primary valve which admits high exhaust to collapse 60 the pneumatic when the re-wind is about to begin thereby producing the result of cutting off the supply of exhaust to the regulated tension chest.

It will be readily apparent to those skilled 65 in the art that the assembly of all of the

described governing and controlling means in the form of a single unit which may be readily applied to the interior of a player piano, presents many great advantages. The adjustment of all the parts respectively 70 and in relation to each other may be readily performed on the bench where all of the parts are most conveniently accessible and the devices may be thoroughly tested separately and collectively as a part of a single 75 unit, conveniently to testing machines,—so that when the unit is ready to be installed in an instrument it has a perfect combination of fully adjusted and operative parts requiring only to have a few simple 80 connections made to other associated parts of the instrument.

For example, the elaborate combination of elements described above may be installed and made an efficient part of the organization of the player piano by merely securing the base plate 10 in place, for instance, in the base of a piano against the inside end of the piano and then connecting the tube 11 with the feeder bellows; the tube 90 12 with the note sheet motor; the tube 12 with the player action chest; and the three bell cranks 68, 78 and 120 with the usual or any appropriate controlling devices located upon the key bed or elsewhere in the 95 instrument, the connections being nothing more, necessarily, than mere link or wire connections. Thus when these units have been assembled in such a combination as that described, they may be shipped in unit 100 form wherever desired and when received they may be installed by entirely unskilled labor and when so installed they will effectively perform the various correlated functions described above. 105

It is to be understood, of course, that this invention is not limited to the specific assembly described above nor to the particular constructions of the different elements described. On the contrary the particular organization and construction may be variously modified and the invention may be variously embodied within the scope of the subjoined claims. It is not indispensable that all the features of the invention be used 110 conjointly since they may be used separately in various combinations and sub-combinations. 115

Claims:

1. A structural unit of controlling apparatus for installation in a player piano or the like, comprising, in combination, a base-board equipped with conduits and having means for connection respectively with a source of exhaust, with the action chest of 120 the player pneumatics and with a note sheet motor; a governor for the note sheet motor and a valve for varying the tempo, both mounted on said base-board and connected with said conduits between the means for 125 130

connection with the feeder bellows and the means for connection with the note sheet motor; an intensity regulator mounted on said base-board, having a valve interposed between the means for connection with the feeder bellows and the means for connection with the action chest of the playing pneumatics; and means for varying playing intensities, also mounted upon said base-board and operatively connected with said conduits:—the whole being assembled in co-operative relation as a unit for installation.

2. A structural unit of controlling apparatus for installation in a player piano or the like, comprising, in combination, a base-board equipped with conduits and having means for connection with a source of exhaust, with the action chest of the player pneumatics and with a note sheet motor; a governor for the note sheet motor and a valve for varying the tempo, both mounted on said base-board and connected with said conduits between the means for connection with the feeder bellows and the means for connection with the note sheet motor; and an intensity regulator mounted on said base-board having a valve interposed between the means for connection with the feeder bellows and the means for connection with the action chest of the playing pneumatics;—the whole being assembled in cooperative relation as a unit for installation.

3. A structural unit of controlling apparatus for installation in a player piano or the like, comprising, in combination, a base-board equipped with conduits and having means for connection with a source of exhaust, with the action chest of the player pneumatics and with a note sheet motor; a governor for the note sheet motor and a valve for varying the tempo, both mounted on said base-board and connected with said conduits between the means for connection with the feeder bellows and the means for connection with the note sheet motor;—the whole being assembled in cooperative relation as a unit for installation.

4. A structural unit of controlling apparatus for installation in a player piano or the like comprising, in combination, a base-board equipped with conduits and having means for connection with a source of ex-

haust and with the action chest of the player pneumatics; an intensity regulator mounted on said base-board having a valve interposed between the means for connection with the feeder bellows and the means for connection with the action chest of the playing pneumatics; and means for varying playing intensities; also mounted upon said base-board and operatively connected with said conduits:—the whole being assembled in co-operative relation as a unit for installation.

5. A structural unit of controlling apparatus for installation in a player piano or the like, comprising, in combination, a base-board equipped with conduits and having means for connection with a source of exhaust and with the action chest of the player pneumatics; an intensity regulator mounted on said base-board having a valve interposed between the means for connection with the feeder bellows and the means for connection with the action chest of the playing pneumatics; means for varying playing intensities, also mounted upon said base-board and operatively connected with said conduits; and a pedal governing apparatus also mounted upon said base-board and operatively connected to said conduits;—the whole being assembled in cooperative relation as a unit for installation.

6. A structural unit of controlling apparatus for installation in a player piano or the like comprising, in combination, means providing operatively connected conduits for connection with feeder bellows and an action chest respectively; and cooperating intensity regulating and intensity varying means structurally united with said first named means and operatively connected with said conduits, the said combination providing a complete unit of intensity governing apparatus which said apparatus as a whole may be regulated and adjusted separately from the player piano and then installed therein and connected with other operating parts.

In testimony whereof, I have signed my name to this specification, in the presence of two subscribing witnesses.
